UNITED STATES PATENT OFFICE.

WILL K. HOLMES, OF TULSA, OKLAHOMA, ASSIGNOR TO THE TEXAS COMPANY, OF NEW YORK, N. Y., A CORPORATION OF TEXAS.

GAS-TIGHT DOME COVER.

Application filed August 31, 1921. Serial No. 497,157.

To all whom it may concern:

Be it known that I, WILL K. HOLMES, a citizen of the United States of America, and a resident of Tulsa, county of Tulsa, and 5 State of Oklahoma, have invented certain new and useful Improvements in Gas-Tight Dome Covers, of which the following is a specification, reference being had to the accompanying drawings, forming a part 10 thereof.

This invention relates to a dome cover for tank cars used in the transportation of volatile fluids such as gasoline and the like.

The invention relates particularly to improvements in gas-tight dome covers of the form shown in my copending application Serial No. 426,720 filed November 27, 1920.

One of the objects of the present invention is to provide quick detachable means 20 for such dome covers which shall secure the same to the body of the tank car in a reliable manner and shall effectually prevent the escape to the atmosphere of the vapors and gases issuing from the volatile liquids 25 within the car.

Another object relates to the provision of a protecting head for such domes, whereby the escape of gases and vapors around the transparent means provided in such domes, 30 is prevented during movement of the car, such gases and vapors being retained within the protecting head until the point of destination of the car has been reached. Thus the danger of fire caused by escaping sparks 35 from the locomotive, is effectually reduced.

Other objects will appear as the description of the invention progresses.

Referring to the drawings:

Figure 1 shows a tank car in position at 40 a filling station.

Figure 2 shows a plan view with the top of the protecting head broken away, and

Figure 3 shows a sectional elevation on the line 3—3 of Figure 2.

Like reference characters denote like parts in the several figures of the drawings.

Referring to Figure 1, there is shown an end view of a tank car 11 in position beside the filling station 13. The tank car is provided with a filling dome 12, and the station comprises supporting means for a charging line and a gas line in a manner well-known in the art.

These comprise a pipe 21 in communication with a suitable source of the liquid

which is to be put into the tank car, and a gas line 22 extending to a suitable compressor (not shown). It is understood that the compressor is in communication with such condensers, tanks, and other apparatus 60 as may be necessary for the compression or absorption of the gases entering the line 22 and which it is unnecessary to show or describe fully herein.

Referring to Figure 3, a preferred embodiment of my invention comprises a circular plate 20 which corresponds to the cover 12^a of my copending application Serial No. 426,720 filed Nov. 27, 1920.

The cover is equipped with a depending flange portion 23 adapted to project within the dome opening while the disc portion of the cover extends across the opening and rests upon the dome rim 24. Projecting through the cover is a charging pipe 25 extending to near the bottom of the tank as shown in Figure 1, and a passage 26 in communication with the interior of the dome.

The disc portion of the cover is provided with a plurality of radial extensions 30, each of which has a notch 31 on one of its radial edges. A bolt 32 is adapted to cooperate with each of these notches and extends into the dome rim 24. A nut 33 on each of the bolts is provided for fastening the dome cover to the dome. Transparent members or windows 72, 73 are provided in the cover for observing and illuminating the interior as fully described in the copending application above referred to, one of said members being provided to admit light to the interior of the tank and the other for permitting the operator or attendant to view the contents of the tank.

The protector head comprises a cup-shaped shell 40 having a flange 41. A plurality of radial slots are cut into the periphery of the flange 41 as shown in Figure 2, and along one edge of each slot is a recess for the reception of suitable fastening means such as a bolt 42 which extends into the body 20 of the dome cover. The nuts 43, are adapted to retain the protector cap in position. A handle 50 shown in section in Figure 3 is provided for conveniently manipulating the protector head. The protector head is fastened to the dome cover by flexible means such as a chain 60 attached at its extremities to links 61 and 62 which 110

are secured to the cover and to the head, in any suitable manner.

In operation the tank car is brought into position at a filling station as shown in Figure 1. The protector head may be removed by removing the nuts 43 and the protector head is allowed to fall into the position shown in Figure 1, being retained therein by means of the chain 60. Suitable hose connections from the supply pipes 21 and 22 are attached to the valves 70 and 71 respectively, and the tank of the car is filled. The hose couplings are then removed and the protector head 40 is put in position over the dome cover and securely bolted thereto.

The car is then sent to its destination in the usual manner. The agitation and vibration to which the contents of the tank car are subjected during such travel, are likely to cause the liquid to be splashed onto the gaskets around the windows 72 and 73 and to seep therethrough. The gas and vapor volatilized therefrom will collect within the cup-shaped member 40 and are effectually protected from the sparks from the locomotive.

Upon arrival at its destination the tank car is placed in position opposite a station similar to that shown in Figure 1, and the hose connections are established as before to pipes corresponding to the pipes 21, 22. The contents of the tank are then withdrawn in the usual manner and the tank car is thus made available for subsequent use in the same manner as before.

Apparatus of preferred form and construction has been illustrated and described for the purpose of showing a way in which this invention may be practiced, but the inventive thought is broader than this illustrative embodiment. It is therefore understood that the scope of the invention is not to be limited by the present disclosure, reference being had to the appended claims for that purpose.

What I claim is:

1. The combination with a tank car dome, of a removable dome cover having a plurality of radial extensions on its periphery, each extension having a notch on one radial edge thereof, means adapted to engage said

notches for securing the cover to the dome, a protector head adapted to be disposed above the dome cover, a horizontally disposed flange integral with the protector head having a plurality of radial extensions, each extension having a notch on one radial edge thereof, and means cooperating with the notches for securing the protector head to the dome cover.

2. The combination with a tank car dome, of a removable circular dome cover adapted to close the dome opening and having a plurality of radial extensions on its periphery, circumferentially arranged means projecting from the dome rim and cooperating with said radial extensions for removably securing the cover to the dome, a protector head having a horizontally disposed peripheral flange adapted to rest upon the dome cover concentric with and inside of the plurality of radial extensions and the dome cover securing means, and circumferentially disposed means projecting from said dome cover and cooperating with the peripheral flange of said protector head for removably attaching said head to said dome cover.

3. A removable gas tight dome cover for loading tank cars, comprising a cover plate or lid having a plurality of radial extensions on its periphery, each extension having a notch on one radial edge thereof, and a depending flange for positioning the cover over the dome opening, a charging line through which liquid is supplied to the tank, a gas or vent line through which inflammable vapors are withdrawn from the tank, a gas tight transparent member or window, an independent gas tight window to admit light to the interior of the tank and to permit observation of the interior through the first named transparent member or window, a protector head having a horizontally disposed peripheral flange adapted to rest upon the dome cover and having a plurality of radial extensions, each extension having a notch on one radial edge thereof, and means cooperating with said notches for securing the protector head to the dome cover.

In witness whereof I have hereunto set my hand this 25 day of August 1921.

WILL K. HOLMES.
